No. 787,380.

Patented April 18, 1905.

UNITED STATES PATENT OFFICE.

CHARLES B. JACOBS, OF PORT CHESTER, AND ROBERT A. WITHERSPOON
AND NATHANIEL THURLOW, OF NIAGARA FALLS, NEW YORK, ASSIGN-
ORS, BY MESNE ASSIGNMENTS, TO CYANIDE COMPANY, OF JERSEY
CITY, NEW JERSEY, A CORPORATION OF NEW JERSEY.

PROCESS OF MAKING ALKALI CYANIDS.

SPECIFICATION forming part of Letters Patent No. 787,380, dated April 18, 1905.

Application filed May 20, 1903, Serial No. 157,968.

To all whom it may concern:

Be it known that we, CHARLES B. JACOBS, a resident of Port Chester, in the county of Westchester, and ROBERT A. WITHERSPOON and NATHANIEL THURLOW, residents of Niagara Falls, in the county of Niagara, State of New York, citizens of the United States, have invented certain new and useful Improvements in Processes of Making Alkali Cyanids, of which the following is a full and complete specification.

Our invention relates to the manufacture of alkali cyanids. Its object is to produce a practically pure alkali cyanid from cyanamids or materials containing cyanamids, and more particularly the cyanamids of the alkaline-earth metals.

In Letters Patent of the United States Nos. 657,937 and 657,938, dated September 18, 1900, and issued to Charles B. Jacobs, are disclosed processes for the making of cyanids of the alkaline-earth metals for use as such or for conversion into the more commonly used cyanids of sodium or potassium. The yield of alkali cyanid which is obtained by these processes is diminished by reason of the presence of the cyanamid of the alkaline earth, together with other impurities. The product obtained by carrying out these processes is found to consist approximately of twenty-five per cent. of barium cyanid and eighteen per cent. of barium cyanamid, together with a mixture of free carbon, barium oxid, a small proportion of barium carbid, some sulfids, and some ferrocyanid. compounds due to impurities in the coal. In the performance of this process hitherto great difficulty has been experienced in separating the barium cyanid from the other compounds present in the furnace product. The presence of barium cyanamid presents particular difficulty on account of its similarity in solubility in ordinary solvents to barium cyanid. The sulfid

and ferrocyanid impurities also interfered with the efficiency of the process by contaminating the finished product. Furthermore, in the ordinary method of lixiviation of the product with a dilute solution of caustic soda or caustic potash the nitrogen fixed in the furnace as barium cyanamid was a total loss, and it was only the nitrogen which entered into the constitution of the barium cyanid which was utilized, since it was only the cyanid which was converted into the sodium or potassium cyanid, and this was contaminated by the cyanamid compound, which greatly interfered in the subsequent production of anhydrous sodium or potassium cyanid.

One of the objects of the present invention is to obviate such difficulties and objections in the processes above referred to and to eliminate the impurities in the finished product.

An important feature of the present invention consists in utilizing all of the nitrogen fixed in the furnace product, including that which enters into the constitution of the cyanamid, as well as that which enters into the constitution of the cyanid, and to utilize the whole of it in the formation of sodium or potassium cyanid.

Our process as applied to the product obtained by the patented processes above referred to consists in the following steps: The furnace product such as is obtained on carrying out the processes disclosed in the before-mentioned Letters Patent and which consists of barium oxid, barium cyanid, barium cyanamid, free carbon, and such impurities as barium sulfid and barium carbid is analyzed to ascertain the exact percentage of barium cyanid and barium cyanamid present. The relative percentages of these two substances may vary between any limits without interfering in any way with the practice of the present invention. According to the result of this analysis a charge

is made up of the furnace product so analyzed, to which is added enough sodium or potassium carbonate to correspond with the following equation:

In carrying out the process without reference to the patents herein mentioned and in working with cyanamids alone the reaction would appear as follows:

Instead of the sodium or potassium carbonate a mixture of sodium and potassium carbonates may be used if it be desired to 15 produce the double cyanid of sodium and potassium. Other suitable alkali compounds may be used instead of carbonate without departing from the invention. In any event it is only necessary to mix the proper amount 20 of alkali carbonate with the furnace product and to thoroughly incorporate the mixture. The mixture is then introduced into a closed retort or covered crucible and brought to a red heat, whereupon the reaction illustrated 25 above takes place and the nitrogen compounds of barium are converted without loss of nitrogen into the alkali cyanid.

The carbon necessary to convert the cyanamid compound into the cyanid may in 30 some cases be the residual free carbon in the furnace product; but as this carbon, owing to the extreme heat to which it has been subjected in the electric furnace, is frequently partially graphitized, and therefore less active chemically than ordinary carbon, it is 35 preferable to add free carbon to the charge in the form of powdered charcoal.

The following is given as an illustrative example of the commercial application of the 40 process for treating one ton of furnace product containing twenty-five per cent. of barium cyanid and eighteen per cent. of barium cyanamid: two thousand pounds furnace product, (containing approximately five hundred 45 pounds $\text{Ba}(\text{CN})_2$ and approximately three hundred and sixty pounds BaCN_2), five hundred and six pounds carbonate of soda, fifty pounds ground charcoal. The above charge is thoroughly ground and mixed and then 50 placed in a closed fusion pot or crucible and raised by external heating to a red heat. The reaction before stated takes place, and approximately four hundred and fifty-eight pounds of sodium cyanid are formed in the 55 fused mass. After cooling the fused mass is ground and lixiviated with water. The resulting solution contains from eight per cent. to a maximum of twenty per cent. of sodium cyanid, depending upon the quantity of 60 water used in lixiviation. The solution also contains barium hydrate, due to the action of water on the barium oxid and barium car-

bid present in the furnace product, some ferrocyanid, and some sulfid compounds. The solution is freed from the barium compounds by precipitation of the barium as a carbonate by treatment with bicarbonate of soda. This results in the introduction of sodium hydrate into the solution in place of the barium salts. The solution is now concentrated ⁶⁵ in *vacuo* until it contains thirty-five to fifty per cent. of sodium cyanid. When concentrated, the specific gravity varies from 1.26 to 1.37, varying with the amount of impurities present. The concentrated solution is now cooled to 20° centigrade, when the small amount of ferrocyanid compounds settle out and are filtered off. The solution is now cooled as low as possible. At a temperature of 5° centigrade a crystallized cyanid of sodium, $\text{NaCN} + 2\text{H}_2\text{O}$, (known to Watt; see *Watt's Chem. Dict.*, Vol. 2, page 347) begins to separate out of the solution, and the separation of pure crystals continues even when the temperature is lowered to -17° ⁷⁰ centigrade. These crystals are drained and centrifugated to free them from the mother liquor which contains the impurities originally present in the solution and some sodium cyanid. The mother-liquor is ⁷⁵ concentrated and a second crop of crystals of sodium cyanid thus obtained. These crystals are not so pure as the first crop and are therefore added to the next lixiviation liquor obtained from a new batch of furnace product ⁸⁰ after the liquor has been freed from barium salts in the usual manner. From this liquor the alkali cyanid is recovered pure in a manner similar to that described above for the first crop of crystals. The mother-liquor is ⁸⁵ reconcentrated and a second crop of crystals of sodium cyanid thus obtained. These crystals are not so pure as the first crop and are therefore added to the next lixiviation liquor obtained from a new batch of furnace product ⁹⁰ after the liquor has been freed from barium salts in the usual manner. From this liquor the alkali cyanid is recovered pure in a manner similar to that described above for the first crop of crystals. Since the impure second crop of crystals remains practically constant and is always obtained in the above-described manner, there is no tendency for the sodium hydrate and sodium sulfid to separate from the lixiviation solution with the first crop of crystals even when the temperature is as low as -17° centigrade. By the above-described process there is therefore obtained only pure crystallized cyanid of sodium. These first crystals so obtained having been freed from the mother-liquor are placed in a vacuum-pan and the water of crystallization driven off, with the result that there is thus obtained pure anhydrous cyanid of sodium or potassium.

While we have described the present process as applied to the furnace product obtained as a result of the processes disclosed in the Letters Patent herein referred to, we desire it to be understood that our present process is not to be restricted to treatment of that product only, but that it may be employed for obtaining in a similar manner pure alkali cyanid from materials comprising the cyanids of

the alkaline earths, together with the cyanamids of the alkaline earths, or from cyanamids alone.

Having thus described our invention, what we claim as new, and desire to protect by Letters Patent, is—

1. The process of obtaining alkali cyanid which consists in reacting upon alkaline-earth cyanids or cyanamids with an alkali compound, forming a solution of the product of such reaction, cooling said solution to a temperature where the alkali cyanid formed separates out leaving the impurities in the solution.

2. The process of obtaining alkali cyanid which consists in reacting upon alkaline-earth cyanids or cyanamids with an alkali compound forming a solution of the product of such reaction, cooling said solution to a temperature of 5° centigrade or lower to separate out the alkali cyanid formed, leaving the impurities in the solution.

3. The process of obtaining alkali cyanid, which consists in reacting upon a cyanamid with an alkali, forming a solution of the reaction mass, concentrating and cooling said solution to a point where the alkali cyanid formed separates out leaving the impurities in solution.

4. The process of obtaining alkali cyanid, which consists in reacting upon a mass containing alkaline-earth cyanids and cyanamids with an alkaline carbonate to convert the cyanids and cyanamids into alkali cyanids, forming a solution of the reaction mass, cooling the solution so obtained, whereby the alkali cyanid resulting from the reaction separates out leaving the impurities in the solution, then separating the alkali cyanid from the solution.

5. The process of obtaining alkali cyanid, which consists in reacting upon a mass containing alkaline-earth cyanids and cyanamids and carbon with an alkaline carbonate, forming a solution of the reaction mass, concentrating and cooling the solution so obtained, whereby the alkali cyanid resulting from the reaction separates out leaving the impurities in the solution, and then separating the alkali cyanid from the solution.

6. The process of obtaining alkali cyanid, which consists in reacting upon a mass containing alkaline-earth cyanids and cyanamids with an alkaline carbonate, forming a solution of the reaction mass, cooling the solution so obtained, whereby the alkali cyanid resulting from the reaction separates out leaving the impurities in the solution, then separating the alkali cyanid from the solution, reconcentrating said solution containing the impurities until a further quantity of alkali cyanid separates out, adding the crys-

tals so obtained to a fresh quantity of lixiviated solution of the reaction mass, concentrating this solution, cooling the same, filtering, and again cooling until sodium cyanid separates out.

7. The process substantially as herein described of treating a mixture of alkaline-earth cyanids and cyanamids with a fixed alkali carbonate at a red heat, thereby obtaining the fixed alkali cyanids, forming a solution of this in water together with the soluble impurities present, concentrating and cooling this solution to a point at which only 75 cyanid of the alkali metal separates out leaving the impurities in solution.

8. The process of obtaining alkali cyanid, which consists in treating a mixture of alkaline-earth cyanids and cyanamids with a fixed alkali carbonate at a red heat, thereby obtaining the fixed alkali cyanids, forming a solution of this in water together with the soluble impurities present, removing from said solution the substances which are less soluble 85 than the alkali cyanids to be produced, by precipitation of said substances with a reagent which leaves in the solution products of greater solubility than the said alkali cyanids, concentrating and cooling this solution 90 to a point at which only cyanid of the alkali metal separates out leaving the impurities in solution.

9. The process of obtaining alkali cyanid, which consists in reacting upon a mass containing alkaline-earth cyanids and cyanamids with an alkaline carbonate to convert the cyanids and cyanamids into alkali cyanids, forming a solution of the reaction mass, treating said solution with a precipitant for the alkaline-earth compounds present, removing said precipitate, concentrating and cooling the solution to a point where only the alkali cyanid separates out leaving the impurities in solution.

10. The process of obtaining alkali cyanid, which consists in treating a mixture of alkaline-earth cyanids and cyanamids with a fixed alkali carbonate at a red heat, thereby obtaining the fixed alkali cyanids, forming a solution of this in water together with the soluble impurities present, treating said solution with sodium bicarbonate, removing the precipitate formed, concentrating and cooling the solution to a point at which only cyanid 100 of an alkali metal separates out leaving the impurities in solution.

11. The process which consists in treating a mixture of alkaline-earth cyanid and cyanamid with an alkali carbonate, heating the mass to a temperature to convert the cyanid and cyanamid to alkali cyanid, lixiviating the mass, precipitating from the solution so obtained the alkaline-earth compounds present,

and concentrating and cooling the solution to a point where only the alkali cyanid separates out leaving the impurities in solution.

12. The process which consists in treating a mixture of alkaline-earth cyanid and cyanamid with an alkali carbonate, heating the mass to a temperature to convert the cyanid and cyanamid to alkali cyanid, lixiviating the mass, precipitating from the solution so obtained the alkaline-earth compounds, and concentrating and cooling the solution to precipitate some of the impurities, removing said impurities, then further concentrating and cooling the solution to a point where only the

alkali cyanid separates out, leaving the remaining impurities in solution.
